UNITED STATES PATENT OFFICE.

WILLIAM JAMES SAWYER, OF WEMBLEY, ENGLAND.

ADVERTISING APPARATUS.

No. 889,814.

Specification of Letters Patent.

Patented June 2, 1908.

Application filed March 17, 1908. Serial No. 421,654.

To all whom it may concern:

Be it known that I, WILLIAM JAMES SAWYER, a subject of the King of Great Britain, and resident of The Gables, Wembley, in the 5 county of Middlesex, England, electrical engineer, have invented certain new and useful Improvements in Advertising Apparatus, of which the following is a specification.

This invention relates to apparatus for the 10 display of advertisements and the like in the form more particularly of transparencies artificially illuminated, the principal object of the invention being to provide improved means whereby a series of advertisements 15 may be exhibited automatically in succession within the same space.

According to the present invention (which for the sake of convenience will be described with special reference to the display of transparencies) each transparency is constituted 20 by or forms part of a curtain or screen which is suspended from and capable of being rolled upon a separate overhead horizontal roller like an ordinary window blind, the curtain 25 being alternately unwound from the roller and thus lowered so as to bring the transparency into exposure position and raised by being wound upon the roller so as to withdraw the transparency behind the upper part 30 of the casing which serves to conceal the working mechanism of the apparatus from sight. This cycle of operations is repeated throughout the series of curtains in succession.

The artificial illumination of the transparencies (when such illumination is employed) 35 is controlled in coördination with the movements of the respective curtains in such manner that illumination continues only so long as an entire transparency remains stationary 40 in exposure position.

I do not limit myself to any particular source of power, but find it convenient to use an electric current, as this affords a ready means for applying electric lamps also, and 45 thus obtaining artificial illumination.

In the accompanying drawings Figure 1 is a side elevation partly diagrammatic showing the preferred form of the apparatus including mechanism for controlling the supply of current to an electric motor and electric lamps alternately. Fig. 2 is a rear elevation of the set of rollers shown in Fig. 1, while Fig. 3 is a fragmentary plan view of part of the mechanism whereby said rollers 50 are successively caused to rotate in opposite directions alternately. Figs. 4 and 5 are re-

spectively side and plan views of a portion of the controlling mechanism shown in Fig. 1, drawn to a larger scale. Fig. 6 is a plan view of another portion of the same mechanism. 60 Fig. 7 is a side view of the fan showing mechanism for adjusting the effective length thereof, and Fig. 8 is a plan view of one of the blades.

Similar references denote corresponding 65 parts throughout the drawings.

The series of rollers A¹, A² etc. upon which the respective curtains B¹, B² etc. are wound, are preferably of equal diameter and arranged horizontally one above another as indicated, 70 each higher roller being mounted parallel to and slightly in advance of the next lower roller so that the curtains, while capable of hanging freely from their respective rollers as shown in the case of B¹, Fig. 1, will ascend 75 and descend in parallel vertical planes which are spaced the minimum practicable distance apart, one directly in front of another. Where a considerable number of transparencies (and therefore of curtains and rollers) 80 are used, the headroom occupied by the apparatus may be economized (at the expense of depth) by the total number being divided into two or more series each similarly arranged one behind another. In the example illustrated the number of curtains and rollers is supposed to be twelve, these being 85 comprised (as shown in Figs. 1 and 2) in two series of six each arranged in the manner described. 90

Each curtain may be stretched flat by its lower edge being suitably weighted (as shown at b in the case of B, Fig. 1,), the weight insuring the prompt descent of the curtain when the roller is rotated in the corresponding 95 direction. The several curtains with the stretching weights b are balanced by means of counterpoises C¹, C² etc. suspended preferably by tapes c which are wound upon barrels D¹, D² etc. at one end of the respective rollers, so 100 that the curtains will have no tendency to move, each roller remaining in any angular position wherein it may be left.

Each roller is positively rotated in both directions, the revolution of successive rollers 105 being so coördinated that while one curtain is being wound up the next succeeding curtain will be in process of being lowered and so on throughout the series in any predetermined order.

Each roller is provided with two separate barrels E¹ and E^{1*}, E² and E^{2*} etc. upon

- which are wound two tapes *e* in opposite directions respectively, the free end of each tape being attached to a separate lever F^1 or F^{1*} , F^2 or F^{2*} etc. and the respective levers 5 being operated alternately at the proper moments, so that each, by pulling upon and unwinding the tape *e* attached to it, will rotate in the corresponding direction the roller to which it appertains, and thus raise or lower 10 the corresponding curtain as the case may be.
- The pairs of levers F^1 , F^{1*} , F^2 , F^{2*} etc. appertaining to the respective rollers are all fulcrumed independently upon a common axis *F* and are guided in vertical planes by 15 working between the bars of a comb-like frame F^* the tapes *e* being guided by a similar frame E^* . The respective levers are operated at the proper times by means of cams G^1 , G^{1*} ; G^2 , G^{2*} etc. mounted upon a shaft *G* 20 which is rotated in one direction, each lever say, for example F^1 , being moved in the active direction by its cam G^1 , and being returned each by the tape *e* attached to it being drawn upon in consequence of being wound 25 up upon its barrel E^1 when the other lever F^{1*} of the same pair is in turn moved in the proper direction by its cam G^{1*} . The several cams may (as shown) be constituted by arms fast upon the shaft *G* and adapted to 30 contact, throughout the requisite arc, with anti-friction rollers *f* carried by the respective levers, the cams being preferably combined in pairs (as indicated in Fig. 3) each serving to operate two adjacent levers whereby 35 respectively one curtain is raised and the next succeeding curtain of the series is simultaneously lowered. In the arrangement illustrated the two end cams of the series are however single.
- 40 The various cams or arms G^1 , G^{1*} , G^2 , G^{2*} etc. are placed side by side upon the shaft *G* opposite to the lever arms F^1 , F^{1*} , F^2 , F^{2*} etc. carrying the anti-friction rollers *f* with which the cams contact, the levers themselves, and therefore also the tapes *e*, being arranged side by side. Hence (with a view to avoiding the employment of a complex system of guide pulleys) it is necessary to 45 arrange the barrels of the pairs E^1 , E^{1*} , E^2 , E^{2*} etc. appertaining to the respective rollers A^1 , A^2 etc. as nearly as may be in the planes of oscillation of the corresponding levers F^1 , F^{1*} ; F^2 , F^{2*} etc. and therefore out of alignment with one another at progressively 50 increasing distances from the common central vertical plane of all the curtains, with the result that the axes of successive rollers A^1 , A^2 etc. of the series from below upwards, require to be made progressively longer.
- 55 These barrels E^1 , E^{1*} etc. (which may be termed the curtain-operating barrels) are preferably all placed at the same end of the apparatus, while the barrels D^1 , D^2 etc. which support the counterweights C^1 , C^2 etc. 60 are placed at the opposite end and in order

to accommodate the several counterweights and permit them to rise and fall freely clear of one another, the counterweight barrels D^1 , D^2 etc. may also be placed out of alignment with one another by progressively lengthening the axes of the respective rollers in the same manner as above described with reference to the curtain-operating barrels. This arrangement is clearly shown in Fig. 2.

The illumination of the transparencies 75 may be effected by means of lamps of any convenient kind placed behind the series of curtains. Preferably however, the light is derived from electric incandescent lamps the circuit through which is broken except during the time an entire transparency remains stationary in exposure position. When such is the case and particularly when (as is assumed in the case under consideration) the cam shaft is also driven by an electric motor 80 supplied with current from the same source of electrical energy as the lamps, advantage may be taken of the fact that the periods of illumination of the transparencies and of their movement into and out of exposure 85 position, never coincide, in order to economize current by shunting the current through the motor and lamps alternately. In order that this may be done, the motor shaft *I* may drive concurrently the shaft *G* already mentioned and also a second shaft *H* having a velocity higher (in the requisite ratio) than that of the first shaft *G* and carrying cams or fingers H^1 , H^2 adapted to actuate, or control the movements of a switch *J* whereby 90 the current is diverted from the circuit of the motor to that of the lamps and vice versa.

According to the preferred arrangement this switch is a two-way mercurial switch 95 constituted by a pair of mercury cups j^2 , j^1 permanently in circuit, separately, with one pole of the source of energy through the motor and lamps respectively, and a two-armed lever J^1 , J^2 permanently in circuit with the other pole of the source of energy and 100 pivoted at *j* so as to be capable of oscillating sufficiently to permit the arms J^1 , J^2 to dip alternatively into the respective mercury cups j^1 , j^2 . The oscillation of the switch lever may be brought about, as indicated, 110 by the pull exerted, in opposite directions alternately, upon cords j^* attached by one end to the respective lever arms J^1 , J^2 and by the other end to a pendulum lever *K* fulcrumed at *k* and carrying a block *k* which, 115 on the completion of each vibration of the pendulum passes between and becomes lightly spring-held by one or other of a pair of stationary elastic retaining jaws K^2 , K^3 as shown more clearly in Fig. 6.

120 For the purpose of causing the pendulum *K* to oscillate rapidly at the proper moments the pendulum lever has an upwardly extending shorter arm *K* which is engaged and moved at intervals, in opposite directions 125

alternately, by tappets L^1 , L^2 whereof the one L^1 is intermittently rotated by a spring (such as indicated at L) wound up at each descent of a curtain and released under the control of 5 an escapement, while the other tappet L^2 forms part of an elbow lever pivoted at l^3 and normally resting by gravity against a stop, the tappet L^2 being operated by the free arm L^3 of said lever being moved by a cam finger 10 H^2 on the shaft H already referred to.

The spring L is coiled about a fixed axis l to which one end of the spring is made fast, its other end being attached to a lever L^4 pivoted upon the same axis. During the 15 latter part of the descent of a curtain, the motor winds up the spring L in consequence of a second finger H^1 fast on the shaft H encountering and moving the lever L^4 which carries a spring-pressed pawl l^4 adapted, 20 during such winding movement to slip idly over the teeth of a wheel l^1 in gear with a pinion l^2 fast on the axis of the tappet L^1 . The winding operation is completed by the 25 time the transparency is brought to rest in exposure position, and at this moment the other finger H^2 on the shaft H comes into operation to actuate that tappet L^2 whereby the 30 pendulum arm K is thrown over so as to break the circuit of the motor and close that of the lamps; the transparency, now brought to exposure position, being consequently illuminated. Simultaneously with the lighting 35 of the lamps, the spring L, now wound up, is permitted (by unwinding itself) to begin driving the train of gearing l^1 , l^2 whereby the other tappet L^1 is brought into operation to again switch out the lamps and switch in the motor.

The tappet L^1 rotates as one with a wheel L^5 in gear with a pinion l^6 (of relatively small 40 diameter) forming part of a train of gearing which serves to drive a fan L^6 whereby the speed at which the spring L runs down is controlled, the wheel L^5 having a gap in its toothed periphery so that the tappet L^1 , after 45 being revolved somewhat slowly until brought into position to engage the pendulum arm K, is at the requisite moment allowed to move rapidly and thus throw the pendulum K over so as to break the circuit of the lamps 50 and close that of the motor. Thereupon the cycle of operations recommences, the motor being re-started so that the transparency just exposed is withdrawn and a fresh one brought to exposure position, and the motor 55 being thereafter stopped while this new transparency is illuminated.

Obviously, the period of exposure and illumination will depend upon the rate at which the spring L is allowed to run down so 60 as to bring the tappet L^1 actuated by it into position to engage the arm K, and any convenient means may be provided for enabling this rate or period to be regulated as may be desired, for example by adjusting the effective length of the blades of the fan L^6 .

It will be obvious that at whatever point in the cycle of operations (in connection with any one curtain) the supply of electric energy may be cut off, the apparatus will always stop either during or just at the commencement of what may be termed the motor-operative period of said cycle, that is to say the stoppage of the apparatus must always occur while the motor circuit is closed at the switch J. As however, it might happen that (during a prolonged interval when the apparatus is out of use) the pendulum K¹ might drop out of engagement with that pair of spring jaws K² or K³ whereby it is held in position to close the motor circuit, means may be provided for preventing such an accident interfering with the automatic restarting of the motor on the subsequent closure of the motor circuit at the main controlling switch provided for starting and stopping the apparatus as a whole. For this purpose the shaft H, which rotates once during the cycle of operations in connection with each curtain, may carry a switch arm M which, at the commencement of the motor-operative period of a cycle, will be brought by the revolution of the shaft H into position to close, for the time being, a shunt circuit passing through the motor, the source of energy, and the main controlling or starting switch. This shunt circuit may obviously be controlled by a separate hand-operated switch. By this means, even supposing the circuit of the motor to be accidentally broken at the switch J, it will be closed at the proper time and during the requisite interval through the switch M, so that on the main controlling switch being brought to the starting position, the motor will commence to work and will automatically bring about the rectification of the conditions as regards the switch J.

The source of electrical supply is connected to the plug R, from which leads the wire V to one pole of the lighting apparatus S and a wire T leads from the other pole of the lighting apparatus to the mercury cup j^1 , the return wire W leading from the switch J, directly to the plug R, a branch wire X leads from the wire V through the motor to the other mercury cup j^2 . It will be evident from the description, that when the switch J is in the position shown in Fig. 1, the motor will be connected with the current and the lighting apparatus will be disconnected.

The shunt circuit in connection with the switch arm M comprises a wire Y branched from the wire W and connected with the switch arm, and a wire Z branched from the wire X, between the motor and the mercury cup j^1 and connected with a spring arm z, the spring arm being adapted to be engaged by the switch arm once during each revolution of the shaft H, to close for the time being the shunt circuit passing through the motor.

Claims

1. The combination of a number of screens adapted to bear advertisements or the like, a number of rollers controlling said screens and so connected with said screens that the latter hang in vertical planes one directly in front of another, a pair of separate barrels for each roller, a pair of flexible connections wound in opposite directions upon said barrels, a number of levers mounted side by side and movable about a common axis, said flexible connections being secured to said levers, said levers being arranged in pairs, and mechanism for actuating said levers in succession for the purpose of causing said curtains or screens to be alternately lowered into and raised out of a predetermined exposed position.
2. The combination of a number of screens adapted to bear advertisements or the like, a number of rollers controlling said screens and so connected with said screens that the latter hang in vertical planes one directly in front of another, a pair of separate barrels for each roller, a pair of flexible connections wound in opposite directions upon said barrels, a number of levers mounted side by side and movable about a common axis, said flexible connections being secured to said levers, mechanism for causing said levers to oscillate, said levers being arranged in pairs, and mechanism co-acting with movements of said levers for illuminating said screens during the time they occupy a predetermined position only.
3. The combination of a plurality of rollers, each roller being provided with a pair of barrels, flexible connections wound oppositely upon said barrels, a screen connected with each roller and adapted to be wound thereupon and unwound therefrom, said barrels overlapping each other and spaced at progressively increased distances from the median line of the rollers, substantially as described.
4. The combination of a plurality of rollers, a screen partially wound upon each roller for the purpose of displaying advertising matter, a pair of barrels for each of said rollers, a flexible connection for each barrel, said flexible connections being arranged in pairs, and wound in opposite directions upon said barrels, levers connected with said connections for turning said barrels and said rollers, and a weight for counterbalancing each screen.
5. The combination of a plurality of rollers, screens mounted thereupon and adapted to be wound and unwound, a pair of barrels for each roller, a pair of flexible connections wound in opposite directions upon said barrels, levers connected with said flexible connections, and a plurality of cams arranged in predetermined positions relatively to each other for the purpose of actuating, in progressive order, said levers.
